COMPASS-FORCEPS FOR SURGERY AND
THE LIKE

Pedro Domingo Curutchet, Loberia, Argentina

Application September 19, 1952, Serial No. 310,515

6 Claims. (Cl. 128—321)

1

This invention relates to a compass-forceps and more particularly to a compass-forceps for surgery to be preferably used for surgery of deep anatomic regions.

The known forceps consist usually of two branches or legs which are elastically connected together at one end. Thus when the forceps is not working, the free end or tips of the branches are separated by an elastic force of a steel spring at the joint. In order to operate said known forceps or more particularly to cause the tips thereof to engage each other, the surgeon's hand must overcome a considerable elastic force which in some instances such as in the case of long forceps reaches about 1,050 g. This considerable effort which is demanded from the fingers of the surgeon's hand produces rigidity of the muscles and thereby decreases the agility and precision of the surgeon's movements. Furthermore when the surgeon grips an anatomic element with such a known forceps the fingers are unable to control the pressure exerted on said anatomic element or part since they have to overcome the powerful elastic force and thereby the kinesthetic sense is impaired.

A further drawback of the known forceps is that during the whole operation it must be employed by the same hand from the beginning to the end and therefore fatigue of the hand and progressive numbness are unavoidable.

A still further drawback is that the length of the known forceps or more particularly of its branches is relatively limited, because upon increasing the length, the force required for closing the tips reaches an inadmissible value.

Bearing in mind the above described and further known drawbacks, a new compass-forceps for surgery and the like has been conceived comprising a top branch having a curved portion and a first tip remote from said curved portion, a bottom branch having a second tip, a pivot pivotally linking said top branch to said bottom branch at a point remote from said first and second tips and adjacent said curved portion, a blade-like grip integral with said bottom branch and located between said pivot and said second tip and a holder integral with said top branch, located between said pivot and said first tip and in the proximity of said blade-like grip when the forceps are in closed position, said first tip and said second tip being normally in contact, and capable of separating and constituting the operative ends of said compass-forceps.

From the foregoing it is apparent that it is an object of the invention to provide a compass-forceps which eliminates the antimanual elastic

2

force of the known forceps, so that the fingers of the surgeon's hand may hold it without the slightest effort and with substantially no possibility of it ever escaping from the grip of the fingers.

In other words, it is an object of this invention to provide a compass-forceps with which it is possible to hold the tips thereof in engagement with just the indispensable pressure to overcome the resistance of the material which is clipped.

Another object is to provide a compass-forceps having cylindrical branches to avoid the discomfort produced to the fingers by the anti-anatomic edges of the known forceps.

A still further object is to provide hollow branches, so that the instrument will be lighter and thus transmit a certain amount of tactile vibration, or in other words to increase the tactile perception of the forceps' work, for instance during dissection.

A further object is to provide a compass-forceps the structure of which enables longer branches to be provided with no detriment to its manuability.

Another object is to provide a compass-forceps which in practice may be held closed indefinitely, thus enabling a wad of gauze to be held for dissecting, and giving rise to a new form of dissection which would be impossible with known forceps. The other hand can thus simultaneously dissect with scissors or a long lancet or by means of a second wad.

A further object is to provide a compass-forceps which may be gripped by either hand since in surgery of deep anatomic regions manipulations become sometimes difficult and complicated, and the hands are frequently compelled to interchange their roles so that an ambimanual instrument is of considerable advantage.

Another object is to provide a compass-forceps which provides agility, easiness and quickness of handling, due to the absence of an elastic force that tightens and stiffens the surgeon's hand.

A further object is to provide a compass-forceps enabling maximum precision to be obtained, because the bottom branch remains relatively stationary and can thus be set and will remain set at the exact point desired.

A still further object is to provide a smooth and efficient digital contact, due to the cylindrical shape of the branches and an anatomic design of the grip and the holder.

Another object is to increase the sensory perception through the transmission by the hollow branches and the blade-like grip.

Still another object is to provide an efficient

hold of the instrument due to the manner in which it is taken, to its ample finger contact on the fluted surfaces of the grip and holder and to the abutment of the top branch against the condyle of the head of the second metacarpal.

Another object is to provide a graduation at will of the pressure at the tips of the forceps, according to the thinness or hardness of the structures, without harming them.

A further object is to provide a compass-forceps the branches of which may be quickly separated under the control of the forefinger, whereas in known forceps this movement is rushed by the drive of the elastic force of the linkage.

Another object is to provide a comfortable hold of the instruments for hours at a time, as it does not demand any exaggerated contraction of the hand muscles, since there is no parasite elastic force.

Still another object is to provide the possibility of dissecting with a wad with the left hand while the right one is dissecting with a lancet or scissors.

These and further objects and advantages will become apparent during the following description in which, by way of example a specific embodiment is described:

In the drawings:

Figure 1 is a perspective view of the compass-forceps of the present invention, as held by a surgeon's hand.

Figure 2 is a side elevation of the compass-forceps of this invention.

Figure 3 is a plan view of the compass-forceps of Figure 2, but with the tip of the top branch cut away.

Figure 4 is a cross-section along line IV—IV of Figure 2.

Figure 5 is a detail in perspective view of the guiding device of the top bottom branches.

Although reference is mainly made to the application in surgery, it is obvious to those skilled in the art that the instrument may be applied to other uses, and thus the scope of this invention must be so understood.

As may be seen mainly in Figures 1 to 3, the compass-forceps for surgery and the like of the present invention comprises a top branch 1 having a curved portion 2 which is an end portion and a first tip portion 3, and a second or bottom branch 4, having a second tip 5. The curved portion 2 ends in a fork 6 in which a projection 7 of the bottom branch is rotatably housed. Both the fork 6 and projection 7 are coaxially 55 perforated forming the housing of a pivot 8 which hinges or pivotally links the top branch 1 to the bottom branch 4.

In the embodiment shown, the clamping surfaces 3' and 5' are serrated (see Figure 3) and have two small perforations 9 in order to provide a positive grip. However the shape and direction of the tips of the compass-forceps may vary, they might be serrated, smooth, perforated, straight, angle-shaped, etc.

The legs or branches 1 and 4 are hollow as may be seen in Figures 4 and 5, so that the weight of the instrument is reduced as much as possible, as previously stated.

In order to hold and adequately control the instrument, the bottom branch 4 is provided with a blade-like grip 10 located between said pivot 8 and said second tip 5 and said top branch 1 is provided with a holder 11. In the embodiment shown, the blade-like grip 10 consists of

two doubly concave blades 12 and 13 substantially symmetrical with regard to a plane of symmetry passing through the center lines axes 14 and 15 of the straight parts of branches 1 and 4. The concavities are directed outwardly and are adjacent to each other, as may be best seen in Figure 3.

The holder 11 is a ring, slightly inclined towards the tip 3 and having an inner fluted surface 16 to prevent the forefinger from slipping as will be later explained. The holder 11 is located in proximity of the blade-like grip 10 but is directed upwardly so that in combination with the blade-like grip 10, the instrument may be held as shown in Figure 1. More particularly the bottom branch 4 is held at three points, namely at the back portion 17, bearing against the condyle of the head of the second metacarpal, at the front by the middle finger 18, resting on one cavity of blade 12 and finally by the thumb 19, resting on one of the concavities of the other blade 13. The proximity of these fingers may vary as required by the degree of precision of the job and that is why the blades 12 and 13 are doubly concave:

The top branch 1 as previously stated, is curved at 2, in order to pass by and bear lightly on the head of the second metacarpal 20. This branch 1 is movable and its tip 3 is moved from 30 and to the tip 5 by actuating movement of the forefinger 21, inserted in the holder or ring 11, which as stated, is fluted at 16 in order to prevent the finger from slipping.

From the foregoing it may be understood that 35 the grip is so universal that it may be held by either hand.

By moving the forefinger 21 upwardly and downwardly the tips 3 and 5 are perfectly controlled in their opening and closing movements.

In order to prevent any lateral dislocation of the tips 3 and 5 and to determine at the same time the limit of separation thereof a guiding device 22 is provided and consists of a rail 23 (see Figure 5) located immediately in front of the grip 10 and having a top projection 24. Said rail may be grooved if desired. The upper branch is provided with a thin shank 25 located immediately in front of holder 11 slidably surrounding said rail 23 and having at the free end 50 projecting ears 26 which are capable of engaging the top projection 24 and thereby limiting the maximum separation of tips 3 and 5.

It is obvious that any other suitable guiding device or pivotal connection may be provided instead of those shown, as long as they comply with the purposes specified. Furthermore the curved portion 2 may obviously be replaced by any other suitable shape, such as for instance a rectangular shape. In order to cover all possible variations concerning said "curved portion" the expression "a pivot distancing portion" for the purpose of this invention is to be understood as broad enough to cover said variations.

65 I claim:

1. A compass-forceps for surgery and the like comprising a top branch having a curved portion and a first tip remote from said curved portion, a bottom branch having a second tip, a pivot 70 pivotally linking said top branch to said bottom branch, at a point remote from said first and second tips and adjacent to said curved portion, a blade-like grip on said bottom branch and located between said pivot and said second tip, and a holder on said top branch located between

said pivot and said first tip on the outer side and disposed to be in the proximity of said blade-like grip when said tips are engaged.

2. A manual compass-forceps for surgery and the like comprising a top branch having a curved portion and a first tip remote from said curved portion, a bottom branch having a second tip, a pivot hinging said top branch to said bottom branch, at a point remote from said first and second tips and adjacent to said curved portion, a grip for the thumb and middle finger of the hand on said bottom branch and located between said pivot and said second tip and a holder for the forefinger of said hand on said top branch and located between said pivot and said first tip and above said grip when said tips are in engagement, said first tip and said second tip being capable of entering in contact with each other and constituting the operative ends of said compass-forceps.

3. A compass-forceps for surgery and the like comprising a hollow top branch having a first end portion and a second end portion, said first end portion being a curved portion having a free end and said second end portion being a first tip having a first clamping surface, a hollow bottom branch having a third end portion and a fourth end portion, said fourth end portion constituting a second tip having a second clamping surface facing said first clamping surface, said free end forming a fork and said third end portion being swingably mounted in said fork, a pivot pivotally linking said fork and third end portion, a grip formed of two doubly concave blades having outwardly directed cavities symmetrical with regard to a plane of symmetry passing through the center lines of said top and bottom branches, said doubly concave blades being on said bottom branch and located between said pivot and said second tip, a ring on said top branch and located between said curved portion and said first tip and adjacent to and above said two doubly concave blades, said ring being inclined towards said first tip, said first clamping surface and said second clamping surface being capable of entering into at least partial contact, and a guiding device for guiding said top and bottom branches.

4. A compass-forceps for surgery and the like comprising a hollow top branch having a first end portion and a second end portion, said first end portion being a curved portion having a free end and said second end portion being a first tip having a first clamping surface, a hollow bottom branch having a third end portion and a fourth end portion, said fourth end portion constituting a second tip having a second clamping surface facing said first clamping surface, said free end forming a fork and said third end portion being swingably mounted in said fork, a pivot pivotally

linking said fork and third end portion, a grip formed of two doubly concave blades having outwardly directed cavities symmetrical with regard to a plane of symmetry passing through the axes of said top and bottom branches, said doubly concave blades being on said bottom branch and located between said pivot and said second tip, a ring on said top branch and located between said curved portion and said first tip and adjacent to and above said two double concave blades, said ring being inclined towards said first clamping surface, said first tip and said second clamping surface being capable of entering into at least partial contact, a guiding device for guiding said top and bottom branches and comprising a rail extending from said bottom branch and located between said grip and said first tip, said rail having a top projection, a shank extending from said top branch and located between said ring and said first tip, said shank being in sliding contact with said rail, said shank having projecting ears for engaging said top projection of said rail and thereby limiting the maximum separation of said first and second tips.

5. A compass-forceps for surgery and the like, comprising a top branch having a pivot distancing portion and a first tip remote from said pivot distancing portion, a bottom branch having a second tip, pivot means pivotally linking said top branch to said bottom branch at a point remote from said first and second tips and adjacent to said pivot distancing portion, a blade-like grip connected to said bottom branch and located between said pivot means and said second tip, a guiding device between said top branch and said bottom branch, and a holder on said top branch, located between said pivot means and said first tip.

6. A compass-forceps for surgery and the like, comprising a rigid top branch having a pivot distancing portion and a first tip remote from said pivot distancing portion, a rigid bottom branch having a second tip, pivot means pivotally linking said top branch to said bottom branch at a point remote from said first and second tips and adjacent to said pivot distancing portion, a blade-like grip on said bottom branch and located between said pivot means and said second tip and a holder on said top branch, located between said pivot means and said first tip.
